United States Patent Office.

TURNER C. PURINGTON, OF LINCOLN, CALIFORNIA.

Letters Patent No. 97,313, dated November 30, 1869.

IMPROVEMENT IN GRAPE-CRUSHERS AND STEM-SEPARATORS.

The Schedule referred to in these Letters Patent and making part of the same.

To all whom it may concern:

Be it known that I, TURNER C. PURINGTON, of Lincoln, Placer county, State of California, have invented certain new and useful Improvements in a Grape-Crusher and Stem-Separator, for which Letters Patent of the United States were granted to me, March 30, 1869 and numbered 88,329; and I do hereby declare that the following is a full and exact description, reference being had to the accompanying drawings, and to the letters marked thereon.

My invention relates to certain improvements in the mechanism for operating the crusher or rubber by a lever, in connection with pivoted toothed segments, as hereinafter described.

In the drawings—

Figure 1 is a side elevation or front view.

Figure 2 is an elevation of the crusher, showing the segmental arm and shaft-bearings in section.

Figure 3 is a sectional view of the rubber or crusher and one shaft-bearing.

To enable others skilled in the art or science to which it most nearly appertains, to make and use my invention or improvement, I will proceed to describe fully its construction and operation.

A represents the segmental pinion, with the shaft S working in the boxes o.

The pinion works in the teeth of the segmental arm B, which is pivoted to the step E, moving on the pin P.

The motion is imparted to the rubber by the lever D, passing through sockets C C, cast with the arm B.

The form of construction of the rubber T, I have found to be of great importance for the perfect working of my machine, and which is nearly flat on the lower face or bottom, with slightly-rounded edges.

In my former specification, I described a half-oval beater; but, by repeated experiments, I much prefer the construction herein shown and described, as the stems will gather better under it, and the grapes will be more rapidly brought to a pulp, and forced through the grated bottom.

The rubber is attached to the axis or shaft S by arms R, which screw into it.

The upper ends of the arms are provided with threads, and pass through the shaft, and have nuts, N, above and below, so that the face of the rubber can be easily raised or lowered to or from the grated bottom.

I have found the to-and-fro or refractory motion, as produced by operating the lever D upon the segmental arm B, the easiest and best method of operating with my machine; and pivoting the arm B in the step E, and attaching the step to the frame and box, as shown, impart strength to the whole machine.

Other power than that of hand-power may be employed for working the beater, although one man can operate with the machine quite easily.

The same general manner of operating with my improvement may be followed as that laid down in my former specification.

Having thus described my invention,

What I claim, and desire to secure by Letters Patent, is—

The beater T, lever D, pivoted toothed segments A, and B B B, when constructed, arranged, and operating together as and for the purpose herein set forth.

TURNER C. PURINGTON. [L. S.]
